ATTORNEY'S

UNITED STATES PATENT OFFICE.

FLOYD J. COLLAR, OF ALAMEDA, CALIFORNIA.

ELECTRIC LOCKING DEVICE.

1,253,788.

Specification of Letters Patent. Patented Jan. 15, 1918.

Application filed July 1, 1916. Serial No. 107,125.

To all whom it may concern:

Be it known that I, FLOYD JUDSON COLLAR, a citizen of the United States, residing at Alameda, in the county of Alameda and State of California, have invented new and useful Improvements in Electric Locking Devices, of which the following is a specification.

My invention relates to certain new and useful improvements in an electric locking device, and it has for one of its primary objects to provide a permutation-lock-controlled switch especially adapted for insertion in the ignition system of internal combustion engines so that the circuit can only be completed by a particular and predetermined arrangement of parts which arrangement is not apparent to the observer.

The invention consists in a novel disposition of operative parts and in details of construction which will be more fully explained by reference to the accompanying drawings in which—

Figure 1 is a top or plan view of the combination disk and turning knob.

Fig. 2 is a section through 2—2 of Fig. 1.

Fig. 3 is a bottom end view of the knob shank and pin.

Fig. 4 is a detail of the flat pressure spring.

Fig. 5 is a bottom view of the dial and change pin.

Fig. 6 is a horizontal section through 6—6, Fig. 2.

Fig. 7 is a section through 7—7, Fig. 2.

As herein illustrated, my invention is designed to be especially applied to lock the ignition current of automobiles, so that only the owner or the one in possession of the combination can start or operate the car or the connected mechanism.

In the drawings, 1 represents the spark plugs or other mechanisms to be controlled; 2 is a generator and 3 is a storage battery in the circuit adapted to supply an electric current when the generator is not in operation. The circuit is completed through the contacts 4 and 5, and the intermediate mechanism, which in the present construction, I have shown as follows: 6 and 7 are disks or movable parts of non-conducting material, superposed and each having pins 8 of conducting material passing through them at points which enable them to register and thus complete a circuit. These disks or movable members may be made of fiber or

of suitable non-conducting material and such may be provided with pins or conducting sections 8 which are so disposed that when the disks have been moved so that the conducting pins or sections are in alignment and contact, the circuit will be closed and when moved out of alignment the circuit will be opened. For convenience of description I have used that form in which the movable members are non-conductors but it should be understood that any equivalent device for producing this result may be substituted without departing from my invention. When the members have been turned to the registering position as shown in Fig. 2, such position is determined by dials *a* and *b* showing letters, figures, or characters, and means by which they may be brought into a certain relation which indicates that the conductors 65 are in line, and the circuit closed.

In the present construction the dial *b* is fixed upon a cylindrical housing 9, within which a cylinder 10 is located. Through the center of the cylinder 10, the spindle 11 extends, and this spindle is turnable by means of a knob 12 on its outer end, and the dial *a* turns with the spindle.

The disks 6 and 7 are located below the cylinder 10 and are shown supported upon a base 13, through which passes a pin 14 that enters the lower end of the spindle 11, the parts 6 and 7 being bored for that purpose.

The disk 7 has a semi-circular groove 7^a made in its surface and extending about half way around. The upper disk 6 has a pin 15 which projects into the groove 7^a and may be turned therein for a purpose, to be hereafter described.

The lower end of the spindle 11 carries a pin 16 which projects eccentric to the center of rotation and which may be depressed to enter a hole 17 whereby the two disks 6 and 7 may be rotated in unison, when the knob 12 and spindle are turned.

The cylinder 10 has a cylindrical chamber exterior to the spindle 11 and a spiral spring 18 is seated in this chamber, its upper end pressing against the dial *a*, acts to raise said dial and the spindle 11, and to withdraw the pin 16 from the hole 17, so that no action takes place if the knob and spindle are turned.

To operate the mechanism, the knob 12 is pushed down, compressing the spring 18 and causing the pin 16 in the lower end of the spindle 11 to ride upon the disk 7 until it

registers with the hole 17, into which it will then fall, and the further rotation of the spindle, will also rotate the disk 7 until the pin 15 projects through the disk 6 into the slot 7^a, in which it travels until it contacts with the end of the slot, and the two disks will then move together until the dials *a* and *b* show the correlation of the desired figures on the dials, which will indicate that an operative contact has been made from 4 with the contact on the disk 6. By then reversing the movement of the spindle, the pin 15 will be carried to the opposite end of the slot 7^a and will then turn this member until its conductor is in line and in contact with the opposed sections 8 when the circuit will be complete from 4 to 5 and an electric current may pass to energize the sparking, or other mechanism controlled by the described devices.

Rotation of the spindle will disarrange the movable members and open the circuit. 19 is a flat-spring so fixed with relation to the member 6 and 7 that one leaf 20 will press against the edge of one member and the other leaf 21 will press against the edge of the other member and the two are thus prevented from being accidentally turned.

The combination may be changed by means of a pin 22 which may be moved to any of the holes 23 of the dial *a* to register with a corresponding character on the dial. 5^a is a spring which is here shown fixed at 5 and extends across and beneath the pin 14, so that when the spindle and pin are depressed, to engage with and actuate the parts 6 and 7, the opposite end of the spring will also be depressed. This end is connected with the conducting section 8^a which being slidable, will be withdrawn, so that when the spindle is depressed, the circuit will be opened and no current can pass to give any indication if the parts are in position, while the movable parts are being operated.

It will be manifest that various changes may be made by those familiar with the art, without departing from my invention.

Having thus described my invention, what I claim and desire to secure by Letters Patent is—

1. In a lock switch, superposed revoluble permutation members having conductor parts, means to turn the members to produce an opened or closed circuit through their conductor parts, said means including a spindle movable to engage with one of the members for turning the same, means by which both members may be engaged to turn together, and a spindle controlled conductor part for opening and closing the circuit through the first named conductor parts, said spindle-controlled conductor part being moved to open position by the spindle on movement of the latter to turn the members.

2. In a lock switch, superposed revoluble permutation members having conductor parts, said members being movable to produce an opened or a closed circuit through their conductor parts, means to engage and turn the members to close the circuit, and means operable by the first means to maintain an opened circuit during the turning of said members.

3. In a lock switch, a body, a base supporting the same, a disk rotatably interposed between the body and base, a conductor part carried by each of the foregoing elements and adapted to electrically connect with each other upon moving the disk into a predetermined relation with the body and base, the conductor part carried by the base being movable from the disk, and a single means for rotating the disk and moving the last named conductor part from the disk.

4. In a lock switch, a movable permutation member having a conductor part, said member being movable to produce an opened or a closed circuit through its conductor part, means to engage and move the member to close the circuit, and means operable by the first means to maintain an opened circuit during the movement of said member.

5. In a device of the character described, a housing, a contained core and electrical terminals, superposed permutation members, a spindle passing through the core and the contiguous member and movable to engage both members and turn them to bring the operative sections into alinement and contact, means to indicate when such alinement is obtained, and elastic pressure means to retain an open circuit while manipulating the permutation members.

6. In a lock switch, a body, a base supporting the same, a disk rotatably interposed between the body and base, a conductor part carried by each of the foregoing elements and adapted to electrically connect with each other upon moving the disk into a predetermined relation with the body and base, a spring yieldably urging the conductor part of the base toward the disk, and a single means for rotating the disk and removing the last named conductor part therefrom.

7. In a lock switch, a body, a base supporting the same, a pair of superposed disks rotatably disposed between the base and body, electrically connectible conductor parts carried by the aforesaid elements, one of said disks having an arcuate cut-out portion and the other disk having a pin extending into the cut-out portion to connect the two disks for movement, and an operating member carried by the body in normally inoperative relation with one disk and movable into operative relation therewith for rotating the same, a conductor part nor-

normally in contact with one of the aforesaid conductor parts and movable out of contact therewith on movement of said operating member to operative position.

- 5 8. In a lock switch, a body, a base supporting the same, a pair of superposed disks rotatably disposed between the base and body, electrically connectible conductor parts carried by the aforesaid elements, one 10 of said disks having an arcuate cut-out portion and the other disk having a pin extending into the cut-out portion to connect the two disks for movement, an operating member carried by the body in normally inoperative relation with one disk and movable into operative relation therewith for 15 rotating the same, and means for removing the base conductor part from the adjacent disk upon movement of the operating member to operative position.
9. In a lock switch, a body, a base supporting the same, a pair of superposed disks rotatably disposed between the base and body, electrically connectible conductor

parts carried by the aforesaid elements, one 25 of said disks having an arcuate cut-out portion and the other disk having a pin extending into the cut-out portion to connect the two disks for movement, an operating member carried by the body in normally inoperative relation with one disk and movable into operative relation therewith for 30 rotating the same, a leaf spring secured at one end to the base and urging the base conductor part toward the adjacent disk, 35 and means carried by the operating member for exerting pressure on the leaf spring to move the base conductor part from the adjacent disk upon movement of the operating member to operative position. 40

In testimony whereof I have hereunto set my hand in the presence of two subscribing witnesses.

FLOYD J. COLLAR.
